United States Patent

Des. 236,823
Patented Sept. 16, 1975

236,823

COMBINED WHEEL CHOCKS AND FLAG

Ralph V. Switzer, 3338 Ravenswood Ave.,
Chicago, Ill. 60657

Filed July 12, 1973, Ser. No. 378,680

The term of this patent subsequent to Dec. 13, 1980,
has been disclaimed

Term of patent 14 years

Int. Cl. D12—16

U.S. Cl. D12—217

Fig. 1.

Fig. 2.

Fig. 3.

Fig. 4.

Fig. 5.

FIG. 1 is a perspective view of the combined wheel chocks and flag, showing my new design;

FIG. 2 is an end elevational view of one of the wheel chocks;

FIG. 3 is a side elevational view of the wheel chock shown in FIG. 2;

FIG. 4 is a view of the opposite end of the wheel chock shown in FIG. 2; and

FIG. 5 is an elevational view of the combined wheel chocks and flag, viewed from the opposite side shown in FIG. 1.

The broken lines are for illustrative purposes only.

I claim:

The ornamental design for combined wheel chocks and flag, as shown and described.
